UNITED STATES PATENT OFFICE.

JAMES F. KELLOGG, OF MITCHELL, SOUTH DAKOTA, ASSIGNOR OF ONE-HALF TO AARON P. GOULD, JOHN C. SKELTON, AND ALBERT HOEFFER, OF CANTON, OHIO.

NECK-YOKE.

SPECIFICATION forming part of Letters Patent No. 471,643, dated March 29, 1892.

Application filed December 3, 1891. Serial No. 413,850. (No model.)

To all whom it may concern:

Be it known that I, JAMES F. KELLOGG, a citizen of the United States, and a resident of Mitchell, county of Davison, State of South Dakota, have invented a new and useful Improvement in Neck-Yokes, of which the following is a full, clear, and exact description, reference being had to the accompanying drawings, making part of this specification.

10 My invention relates to improvements in pole-tips and neck-yoke rings, the object of which is to provide means by which the pole may be securely supported and accidents obviated, as will be hereinafter set forth.

15 With these ends in view my invention consists of certain features of construction and combination of parts, as will be hereinafter described, and pointed out in the claim.

Figure 1 of the accompanying drawings is 20 a view in perspective of a pole-tip and neck-yoke ring, illustrating my invention; Fig. 2, a section through the pole-tip and neck-yoke ring; Fig. 3, a view comprising a clasp to embrace the yoke and the neck of the ring, a 25 fragment of which is shown.

Letters of reference indicate corresponding parts in all of the figures of the drawings.

A represents a wagon-pole, having at its front end a metallic tip or thimble portion B 30 to embrace the end of the pole. About said tip is provided an annular flange or stop C. The neck-yoke D is turned tapering from a central line, as a, to the ends. A clasp, as E, is provided having portions b b', adapted to 35 embrace the yoke and conform to the taper on either side of the line a, by which end movement of the clasp is prevented. As shown, the two portions b and b' of the clasp are connected by an offset portion c, in which 40 is provided semicircular portions d d, which when the flange portions e are brought together and secured by rivets, as shown in Figs. 1 and 2, will form a circular aperture or ring adapted to embrace the neck portion of the 45 dog F, link C, or yoke-ring H, by which construction the parts F, G, and H are swiveled to the yoke. To the dog F is pivotally secured the yoke-ring H, at the lower portion of which

is provided a hook f to engage the flange C in operating the parts, as shown in Fig. 1. 50 While the yoke is free to swing or swivel about the dog F, a forward movement will cause the lower end g of the dog F to bite or engage the tip B and raise the hook f up to engage the flange C, thus securely holding 55 the yoke in engagement with the pole.

Calling attention to what is shown in Fig. 2, which differs from that shown in Fig. 1 only in removing the lower end portion z of the dog F, the upper end portions serve as a 60 link J, by which the yoke is allowed to swing forward and back over the ring H, which is secured to the flange C by the hook f.

For close hitching or carriage-work I prefer that the ring H have formed thereon a neck, 65 as h, and head g and hook f, diametrically opposite the neck, to be embraced by the semi-circular portions d d of the clasp e, thus forming the ring H and the yoke, the hook f to engage the flange C, by which the yoke is secured 70 to the tip and pole.

The prime object of my invention, as has been shown and described, is to provide a practical and inexpensive means by which the pole of a wagon may be secured from falling and the team secured thereto in the case of a detached lug or the breaking of a single-tree, thereby preventing serious injury and probably loss of life and property. 75

What I claim as new, and desire to secure 80 by Letters Patent, is—

The combination, with a pole and neck-yoke of the tip provided with a stop C, of a dog or pawl having one of its ends connected with the yoke by a swivel-joint, the other to have a biting 85 engagement with the tip, a ring H, pivotally secured to said dog, and the hook f to engage the stop C, substantially as described, and for the purpose set forth.

In testimony whereof I have hereunto set 90 my hand this 23d day of October, A. D. 1891.

JAMES F. KELLOGG.
